UNITED STATES PATENT OFFICE

2,623,495

APPARATUS FOR COATING SCROLLED SHEETS

Scott R. Johnson, River Forest, Ill., assignor to
 Continental Can Company, Inc., New York,
 N. Y., a corporation of New York

Application January 16, 1947, Serial No. 722,387

3 Claims. (Cl. 118—6)

1

The invention relates generally to the art of forming end closures for cans or similar containers and it primarily seeks to provide a novel apparatus for coating the scrolled sheets which are subsequently cut into the individual scroll strips from which said end closures are punched.

It is quite common in the art to successively feed individual scroll strips to a punch press for cutting can ends from the strips and properly die shaping the same. When strips having parallel line side edges and continuous end edges bearing right angular relation to said side edges are used much unnecessary wastage of metal is occasioned because of the straight side and end edges, particularly when the ends are punched from the strips in longitudinally and transversely aligned rows. In order to reduce this wastage of metal between punch rows, the punching of the ends has been performed by punches so placed as to stagger the rows so that each punch hole in a given row is centered between two hole centers in an adjacent row thereby to permit the row centers to be brought closer together, but with this arrangement one opening at the end of each row is spaced a considerable distance from the adjacent end edge of the strip and unnecessary wastage is occasioned at said ends unless some provision is made to avoid the same. It has been found that by cutting coil stock transversely at sheet lengths by a scroll cutter, scrolled sheets can be formed which can be turned 90° and fed step-by-step through scroll shears for having scroll cuts made transversely thereacross so as to divide said sheets into multiples of scroll strips in which most of the wastage referred to will be eliminated in the subsequent cutting of the end closures therefrom.

Scrolled sheets of the character referred to commonly have burrs along the scrolled edges thereof, and when it is desired to coat said sheets with protective lacquer or comparable coatings after the sheets have been severed from the coil stock, said burrs have presented problems due to the formation of scroll line depressions in the coating rolls and the resultant application of heavy coating accumulation along the scrolled edges of the sheets. It has been found that repeated contacts of the deformable coating applicator surface of a coating roll with the scrolled edges of the sheets incidental to the coating of said sheets caused the scrolled edge burrs to form a scrolled groove or depression in the roll, and as a result of accumulation of coating material in said groove an excess or accumulation of the coating material was deposited along the

2

scrolled edge extremities of such sheets. This accumulation of coating material was found very objectionable during the punching of can ends from the subsequently formed coil strips because said material would chip off and foul the punching die equipments.

Therefore it is an object of the present invention to provide a novel apparatus for coating scrolled sheets which will avoid the formation of scrolled grooves in the coating rolls and also avoid the application of an excess or accumulation of coating material along the scrolled edge extremities of said sheets.

More specifically, the invention seeks to provide an apparatus of the character stated including sheet supporting means, sheet feeding means, a coating applicator roll having an applicator surface thereon adapted to engage in rolling contact with and coat the all-over surface of each fed sheet and including scroll cut edge portions corresponding substantially to the pattern of the scroll cut edge portions of each sheet and dimensioned so as to be registrable with the scroll cut edges of sheets with all portions of the scroll cut edge portions of said applicator surface close to but spaced inwardly from all portions of the scroll cut edge portions of said sheets, and means to register the scroll cut edges of the fed sheets with the scroll cut roll edge portions so that the latter will coat the scroll cut edges of the sheets close up to but just short of each edge extremity defining said scroll cut sheet edge portions.

With the above and other objects in view that will hereinafter appear, the nature of the invention will be more clearly understood by reference to the following detailed description, the appended claims, and the several views illustrated in the accompanying drawings.

In the drawings:

40 Figure 1 is a plan view illustrating a scrolled sheet which is to be coated in accordance with the invention.

45 Figure 2 is an enlarged fragmentary view illustrating a portion of the sheet shown in Figure 1 coated in accordance with the invention.

Figure 3 is a fragmentary somewhat diagrammatic development of the coating roll surface showing the relation thereof to a sheet being coated.

50 Figure 4 is an enlarged fragmentary view illustrating the coated material applying surface of the roll at one end thereof, a fragment of a scrolled end sheet being superposed thereover in registered relation.

55 Figure 5 is a somewhat diagrammatic longi-

tudinal sectional view illustrating an example apparatus embodying the invention.

Figure 6 is a side elevation illustrating drive connections in the apparatus shown in Figure 5.

In Figure 1, there is illustrated one of the scrolled sheets which is to be coated in accordance with the invention, said sheet being generally designated 5. Such sheets preferably are formed by feeding a continuous strip or web of metal from a coil in the direction of the arrow 6 on Figure 1 and scroll shear cutting said strip or web transversely to form individual sheet lengths such as are shown in Figure 1. This manner of forming the scrolled sheets provides scroll cut end edges arranged in parallel relation and presenting alternated projections 7 and recesses 8, the center of each projection at a given end of the sheet being in line with the center of a depression at the opposite end of the sheet in the manner clearly illustrated in Figure 1.

After the scrolled sheets of Figure 1 are formed in the manner stated, they may be fed in the direction of the arrow 9 on Figure 1 for being coated in the manner hereinafter described, that is with the scroll cut edge portions thereof presented toward the sides, and with the parallel straight end edges presented at advance and trailing edge portions. After the scrolled sheets are coated in the manner hereinafter described and baked they are fed, step-by-step in the direction of the arrow 9 to a scroll shear for having scroll cuts made thereacross for the purpose of dividing the sheet into individual scroll strips. The first cut of the shears will provide a scroll edge trim cut as at 10, and the transverse scroll cuts made successively thereafter as at 11 will serve to divide the sheet into individual scroll strips which are later to be fed individually and lengthwise in the direction of the arrow 6 to the punch and die equipments which punch ends therefrom in the manner indicated at 12 in Figure 1. It will be apparent that by staggering the rows of punch cuts, and scroll cutting the sheet and strip edges, a minimum of waste or scrap is provided.

It will be apparent by reference to Figure 2 of the drawings that the protective or decorative coating of lacquer or the like applied to the scrolled sheet shown in Figure 1 covers the whole surface of the sheet at one face thereof except for a very narrow marginal edge portion which follows the contour of the scroll cut edges and is left plain or uncoated. The all-over coated surface is indicated at 13 and the very narrow uncoated marginal edge portion is indicated at 14. It will be apparent by a comparison of Figures 1 and 2 of the drawings that the leaving of the very narrow marginal edge portion uncoated is not objectionable because any overlapping of a punch cut into the narrow uncoated margin will be very slight and will be at that extreme edge portion of the end closure which is rolled into a seam in the attachment of the end closure to a can.

In the coating of the scrolled sheets in the manner hereinabove described, a coating roll such as is shown in Figures 3 and 4 of the drawings may be employed. The coating roll may include a shaft 15 surrounded by a core or body 16 which is in turn surrounded by a blanket or applicator sleeve 17 of the slightly yieldable applicator surface material customarily employed in coating rolls. The applicator sleeve 17 has its end portions scroll cut as at 18, and it is important to note that the scroll cut portions of the applicator roll ends are slightly shorter and narrower than

the scroll cut edge portions of the scrolled sheets which are to be coated by the roll. In this manner as the applicator roller engages in rolling contact with the scrolled sheet with the scroll edges of the sheet and the scroll cut end portions of the roll in proper registry, the coating material will be applied in the manner clearly illustrated in Figure 2 with the coating 13 terminating within the borders of the sheet and close to the scroll cut edges thereof in a manner for leaving the very narrow uncoated marginal edge portions 14 as shown in said Figure 2.

It is to be understood that any suitable apparatus may be employed for engaging the coating roll surface with the scrolled sheets in proper registry in the manner hereinabove described, and an example of apparatus which will be found satisfactory for the purpose stated is to be found in the Wagner et al. Patent 1,848,856 issued 20 March 8, 1932. When an apparatus of this type is employed it may include bearing means 19 for rotatably supporting the coating roll in suitable framing 20. The applicator sleeve 17 of the roll may be engaged by a transfer roll 21 which 25 transfers the coating material picked up and applied thereto by the pick up roll 22 which has its lower portion immersed in the coating material 23 contained in the reservoir 24 supported on the frame structure.

The applicator roll operates over a bed roll which has suitable rotative support in the framing, and the scrolled sheets may be fed over suitable table means 26 into the bight between the bed roll 25 and the applicator sleeve 17, said 30 sheets being suitably guided by guide means 27 disposed to engage the scroll cut side edge portions of the sheets. In the patent disclosure referred to, the guide means take the form of laterally reciprocable devices, but it is to be understood that fixed guide means may be employed, if desired.

The scrolled sheets may be fed into the apparatus by hand, or on a conveyor 28 which may feed them into the apparatus and against a stop means 29. The stop means shown is carried by a rock shaft 30 which is rockable to oscillate the stop means into and out of the path of the in-feeding sheets. In other words, the stop will intercept a sheet, and then at the proper time release the same to permit it to move into the apparatus in properly timed relation. The oscillatable stop means operates in combination with a magnetic entry roll 31 and each time the stop means is lowered so as to release an incoming sheet, said roll serves to feed the released sheet into the apparatus and onto the feed chains 32 which are equipped with feed fingers 33 effective to feed the sheets to the rolls in accurately timed relation.

Magnetic feed rolls 34 and 35 may be provided, one thereof being disposed transversely of the apparatus in advance of the rolls 25 and 17, and the other of said rolls being similarly disposed beyond said rolls 25 and 17. Lifter fingers 36 60 cooperate with the magnetic feed roll 34 and are normally positioned at an elevation for holding a sheet end above and out of contact with the roll 34. The fingers are oscillated upwardly and downwardly in timed relation with the movement 65 of the coating roll so as to at the proper time lower sheets onto the feed roll so that the feed rolls 34 and 35 can take over the feeding of sheets in proper timed relation to the movement of the scroll cut coating roll. The lifter fingers 36 are 70 mounted on a transversely disposed rock shaft 75

37 and rocking movement is imparted to the shaft by engagement of the roller 38 on the arm 29 with the rotary cam 40. The cam 40, best shown in Figure 5 of the drawings, is driven through a gear couple 41 from the cross shaft 42 which is also connected in driving relation, through the gear couple 43, with the side gage operating cam means 44.

It will be apparent by reference to Figure 6 of the drawings that the drive shaft 45, driven in any approved manner (not shown) is connected in driving relation, through sprocket and chain connections 46, with the shaft 47 which is in turn connected in driving relation by the gear couple 48 with the shaft 49. The shaft 49 drives the shaft 50 through the gear couple 51, and the shaft 50 drives the coating roll through the gear couple 52, and also the bed roll shaft through connection of the gear 53 with the lowermost one of the meshing gears 52. The bed roll shaft in turn drives the magnetic feed rolls 34 and 35 through the gear train 54.

The lowermost one of the meshing gears 52 drives the chain driving cross shaft 55 through the gear train 56, and the shaft 55 is connected in driving relation with the magnetic entry roll 31 through the power transmission connections 57.

A cam 58 on the shaft 50 operates through pitman and crank connections 59 to impart rocking movement to the previously described rock shaft 39 on which the stop fingers 29 are mounted.

Scrolled sheets coated in the apparatus may be delivered therefrom by the discharge conveyor 60 which may be arranged to deliver said sheets directly onto the wickets 61 which carry them into and through the usual baking oven.

By use of the disclosed apparatus or an equivalent apparatus including the scroll cut coating roll and means for feeding the sheets to and accurately registering them with said roll during the coating process, the desired coated scrolled sheet can be provided with the coating thereon extending close but not all the way up to the scroll cut edge extremities at the sides of the sheets, and by registering the sheets as they are being coated in the manner herein described, with the side edges of said sheets slightly overhanging or extending beyond the side edges of the coating roll, all chance of the burrs on the scroll cut edges of the sheets engaging with the deformable coating surface of the roll and forming a groove therein which would be effective to collect and apply a surplus of coating material to the scroll cut edges of the sheets is avoided.

While example apparatus has been disclosed herein, it is to be understood that the specific form of apparatus may be varied without departing from the spirit and scope of the invention as defined in the appended claims.

I claim:

1. In apparatus for coating sheets of metal having the side edges thereof scroll cut, sheet supporting means, sheet feeding means, a coat-

ing applicator roll having an applicator surface thereon adapted to engage in rolling contact with and coat the all-over surface of each fed sheet and including scroll cut edge portions corresponding substantially to the pattern of the scroll cut edge portions of each sheet and dimensioned so as to be registrable with the scroll cut edges of sheets with all portions of the scroll cut edge portions of said applicator surface close to but spaced inwardly from all portions of the scroll cut edge portions of said sheets, and means to register the scroll cut edges of the fed sheets with the scroll cut roll edge portions so that the latter will coat the scroll cut edges of the sheets close up to but just short of each edge extremity defining said scroll cut sheet edge portions.

2. In apparatus for coating sheets of metal having the side edges thereof scroll cut, sheet supporting means, sheet feeding means, a coating applicator roll having an applicator surface thereon adapted to engage in rolling contact with and coat the all-over surface of each fed sheet and including scroll cut edge portions corresponding substantially to the pattern of the scroll cut edge portions of each sheet, and means to register the scroll cut edges of the fed sheets with the roll edge portions, said scroll cut roll edge portions terminating substantially parallel and short of each edge extremity of the scroll cut sheet edge, thereby to leave an uncoated margin of very narrow width on each sheet along the scroll cut side edges and causing said side edges to extend beyond and out of contact with the coating applicator surface of said roll.

3. In apparatus for coating sheets of metal having the side edges thereof scroll cut, sheet supporting means, sheet feeding means, a coating applicator roll having an applicator surface thereon adapted to engage in rolling contact with and coat the all-over surface of each fed sheet and including scroll cut edge portions corresponding substantially to the pattern of the scroll cut edge portions of each sheet, and means for cooperatively timing the sheet and roll movements to cause the scroll cut edge portions of the sheets and the roll to register accurately, said coating applicator surface of the roll being so dimensioned that the coated surface on each sheet will terminate within the borders of the sheet and close to the scroll cut edges thereof.
